UNITED STATES PATENT OFFICE.

MAX RUMPF AND WILLIAM E. NIMZ, OF CHICAGO, ILLINOIS; SAID NIMZ ASSIGNEE TO
SAID RUMPF.

HAND STAMP.

1,405,444.

Specification of Letters Patent. Patented Feb. 7, 1922.

Application filed January 21, 1921. Serial No. 438,832.

To all whom it may concern:

Be it known that we, MAX RUMPF and WILLIAM E. NIMZ, citizens of the United States, residing at Chicago, in the county of Cook and State of Illinois, have invented certain new and useful Improvements in Hand Stamps, of which the following is a specification, reference being had to the accompanying drawings, forming a part 10 thereof.

The purpose of this invention is to provide an improved construction of a hand-operated stamp carrying a plurality of printing elements and adapted to be adjusted to bring any selected printing space into printing position, a specific purpose of the invention being to provide improved means for selecting and setting at printing position the desired printing face. It consists of the 20 elements and features of construction shown and described as indicated in the claims.

In the drawings:

Figure 1 is a top plan view on a reduced scale of a stamp embodying this invention. 25 Figure 2 is a section at the line, 2—2, on Figure 1 on a larger scale.

Figure 3 is a section at the line, 3—4, on Figure 2, showing the parts at rest position.

30 Figure 4 is a section at the same plane as Figure 3, showing the parts at printing position of the stamp.

Figure 5 is a section at the line, 5—5, on Figure 2.

35 Figure 6 is a developed plan view of the manual segment or key-board and rocking key-stopped segment, which co-operates therewith, these segmental parts being each shown as they would appear if extended 40 into flat form, the segment being partly broken away and its supporting arm at one side sectioned to disclose the other segment.

Figures 7, 8 and 9 are sections at the same 45 plane as Figure 5, omitting the key-board segment and co-operating rocker, and actuating connections of the latter,—and showing the ink-pad operating parts in three positions.

Figure 10 is a vertical transverse section 50 of the ink-pad carrier.

Figures 11 and 12 are side elevations of certain parts concerned in the movements of the ink-pad carrier.

Figure 13 is a plan view of the ink pad on the bottom bar of the pad carrier. 55

Figure 14 is a section at the line, 14—14, on Figure 2.

Figure 15 is a side elevation of one of the cam lever arms employed for upholding the plunger at one stage of the operation 60 of the stamp.

Figure 16 is a section at the line, 16—16, on Figure 3.

Figure 17 is a plan view of one of the stamps. 65

Figure 18 is a section at the line, 18—18, on Figure 2.

Figure 19 is a section similar to Figure 2 of the upper part of the standard and parts therein, including certain additions to the 70 structure shown in the preceding figures.

Figure 20 is a section at the line, 20—20, on Figure 19.

Figure 21 is a section at the line, 21—21, on Figure 19. 75

Figure 22 is a section at the line, 22—22, on Figure 20.

Figure 23 is a section at the line, 23—23, on Figure 21.

Figure 24 is a detail elevation looking in 80 the direction of the arrow on Figure 22.

Figure 25 is a detail elevation looking in the direction of the arrows on Figure 23.

In the construction shown in the drawings, A is a frame or standard comprising a 85 crosshead, 1, and uprights, 2, 2. B is a plunger comprising a stem, B¹, which has a bearing at a, in the cross-head of the standard, A, and which itself comprises a cross-head, 5, sectoral side limbs, 6, 6, and a cylindrical 90 segmental web, 7, which constitutes what may be called a key-board for the operating buttons of certain manually operable keys, hereinafter described, for setting the stamp-carrying rotor at selected positions for presenting the desired printing face in printing position. The plunger is guided in the standards by means of the ends, 9^a, of the shaft, 9, constituting trunnions engaging the vertically extending slots, a¹, a¹, in the 100 uprights, 2, 2, of the standard. The shaft, 9, extends through both limbs, 6, 6, of the plunger, and may be either loose or fast in these limbs, but in either event, it is longitudinally checked and retained in the 105 structure by flanged nuts, 10, 10, screwed

onto its protruding ends outside of the uprights, 2, 2, of the standard. On the shaft, 9, between the limbs, 6, 6, of the plunger, there is mounted for rotation the rotor, C, 5 which is polygonal in transaxial section, having parallelogrammatic faces suitably provided with means for holding interchangeable or removable stamping or printing plates, 15. For mounting the rotor on 10 the shaft, it has itself a hollow shaft, comprising the two members, 14 and 15^a, interlocked with each other by the tongues, 14^a, of the part, 14, which engage notches in the part, 15^a. One head, 17, of the rotor is 15 cured to the shaft member, 15^a, by abutting against and being secured to a collar, 15^b, made fast on said member, 15^a. The other head, 17^a, of the rotor has a central depression forming a spring chamber, 17^c, for accomodating a spring, 18, provided for a 20 purpose hereinafter explained, and is secured to the hollow shaft member, 14, by riveting onto the end of the latter as seen at 17^b. The inner diameter of the part, 14, is 25 adapted for journaling upon the shaft, 9. At the opposite end of the rotor shaft member, 15^a, there is telescoped within it and made fast to it, operating as a bushing within it and affording it journal bearing on the 30 shaft, 9, a sleeve hub, 19^a, of the pinion, 19, between which pinion and proximate end of the shaft member, 15^a, there is interposed a spacing washer or collar, 20. The pinion, 19, is thus made rigid with the rotor. D is a 35 rocker comprising a cylindrical segment web, 25, having sectoral radius arms, 25^a and 25^b, by which said rocker is mounted for rocking about the shaft, 9, and coaxially with the rotor, C. One of said sectoral radius arms, 25^a, is journaled directly upon the 40 shaft, 9, and the other, 25^b, is journaled upon the opposite end of the rotor shaft member, 15^a, between the head, 17, of the rotor and the spacing washer or collar, 20, 45 a spacing washer, 20^a, being interposed between said radius arm and the collar, 15^b, of the rotor head. Upon the left-hand sectoral radius arm, 25^b, there is provided a segment rack, 26, in the plane of the pinion, 50 19; and upon the left-hand side limb, 6, of the plunger there is journaled a gear, 27, which meshes with the rack, 26, and with said pinion, 19, for rotating the pinion by the rocking of the rocker, D, about the shaft. 55 The arc of the segment member, 25, and of the rack, 26, and the angle through which said rocker may rock are calculated with respect to the pinion, 19, so that the rocking of the segment through the angle provided 60 for will give the pinion, 19, and thereby the rotor, C, one complete revolution; and thereby brought to printing position. As a matter of fact, as most conveniently, and therefore preferably, constructed, the driving action proceeds from the pinion to the gear

through the segment rack rather than in the reverse direction; but this is immaterial for the result. The preferable connection of the spring is as shown, that its inner end is attached to a pin, 35, which projects from the adjacent radius arm, 25, of the rocker, D, and its outer end is hooked into the circumferential wall of the depression, 17^c, in the right-hand head of the rotor, C, at 17^b. The parts thus geared together,—that is, the 70 rotor, C, and the rocking segment member, D, are locked at what may be called the normal position,—with printing plate No. 1, of the rotor in printing position,—against the reaction of the spring tending to rock the 75 rocker, D, and rotate the rotor away from that position, by means of a dog engaging a stop abutment, d, on the right-hand radius arm, 25^a, of said rocker, D. The dog consists of the right-hand wing or arm, 29^a, of a member which is mounted for rocking on the plunger, consisting of a bar, 29, having at its opposite ends, folded at right angles to it, forming wings, 29^a and 29^b, which are pivoted respectively on the two opposite 80 limbs, 6, 6, of the plunger, as seen at 29^a, the right-hand wing being deflected as seen at 29^b, and having its extremity turned inward parallel to the shaft axis forming a nose, 29^c, for encounter with the stop, d, as 85 stated. A spring, 30, attached at one end to the arm, 29^a, stretched to engage a pin, 30^a, on the plunger limb, 6, tends to hold the nose, 29^c, of the dog, 29^a, in position for encounter and engagement with the stop, d. It will be seen that upon depressing the bar, 29, causing disengagement of the dog, 29^a, from the stop, d, the reaction of the spring, 100 18, will tend to rock the rocker, D, and rotate the rotor, C, through an angle determined by the point at which the rocking movement of the rocker, D, is arrested. For arresting this rocking movement at the different positions corresponding to the printing position of the several printing faces of 105 the rotor, there are provided a plurality of keys, 40, one for each printing face of the rotor except face No. 1; said keys being sprung bars secured at one end to the inner 110 face of the segment web, 7,—called the keyboard,—of the plunger and extended around under said segment web in the direction of rotation or rocking of the rocker, D. Each of said keys has its free extremities bent inward radially with respect to the rotor and 115 rocker; and the segment web, 25, of the rocker has a corresponding plurality of slots, 25^a, all terminating at the same line parallel to the axis at which the radially in-bent terminals, 40^a, of the keys, 40, stand, and extending back from said point through arcs corresponding or proportionate to the angular movement of the rotor necessary to bring the several printing faces respectively, to 120 printing position. Each of the keys, 40, has 125 130

an operating button, 41, extending in through the segment web, 7, constituting the key-board, said key buttons being arranged staggered in two rows; all the keys, 40, extend across the bar, 29, of the member which comprises the dog, 29^a; and it will be seen that upon the depression of any key, said dog will be disengaged from the stop, *d*. At the same time the in-turned end, 40^c, of the key is inserted in the slot corresponding to that key in the segment web, 25, and the length of the slot therefore limits the angular rocking movement of the rocker, D, which will result from the release of the dog, 29^a. According to the key selected for depression therefore, will be the angle of rotation of the rotor; and the buttons, 41, being marked to indicate the printing faces to which they respectively correspond, the operator will readily select the stamp to be imprinted. It will be obvious that other means beside slotting the segment, 25, may be employed for affording the stops for encounter with the in-turned ends, 40^c, of the key-bars, which in the construction described is afforded by the end of the slot. A reason for preferring the slot, however, is that thereby it is rendered easy to provide for retaining the key depressed until the rocker, D, is rocked back to its normal position. This is accomplished by furnishing the downturned end, 40^a, of the key bar, with the T-cross, shown at 41^a, and enlarging the slot opening seen at 25^c, to admit the cross of the T which engages under the margins of the slot and retains the key depressed until the rocker is again rocked back to the position at which the key was entered, and at which it may escape through the enlargement, 25^e.

For returning the rocker, D, to normal position after the stamp has been operated to imprint with the face which has been set at printing position, there is provided on the standard at one side a vertical rack, 50; and mounted for rocking over the shaft, 9, there is a member which comprises a gear segment, 51, and a radius arm, 52, the gear segment meshing with the rack, 50, and the radius arm extending up alongside the right-hand radius arm of the rocker, D, carrying at its upper end a latch, 53, which has a radius arm, 54, connected by a stretched spring, 55, with a pin, 56, on the radius arm, 52, operating to hold the latch with said arm, 54, stopped against a pin, 58, on the arm, 52, of the segment. The latch, 53, is carried by the radius arm, 52, alongside the radius arm, 25^a, of the rocking member, D, and having a catch nose, 53^a, adapted to snap into engagement with an abutment, 25^c, which projects from the said radius arm, 25^a, of the rocker, D. This abutment is positioned so that in the extreme position to which the rocker, D, may be rocked away

from normal position,—to bring the printing face, 9^b, into printing position, the catch nose, 53^a, would be carried past it by the rocking movement which the radius arm, 52, will receive by the engagement of the segment, 51, with the rack, 50, in the printing stroke of the plunger, the distance to which said nose will pass said abutment, 25^c, in said printing stroke being greater as the rocking angle of the rocker, D, is less for bringing any of the lower numbered printing faces to printing position. It will be seen, therefore, that in the retracting movement of the plunger, after the printing stroke, causing the radius arm, 52, carrying the dog, 53, to be rocked back, the catch nose, 53^a, will pick up the abutment, 25^c, and will rock the rocker, D, back to normal position. The parts engaged in this operation are so positioned relatively that in fact the retracting movement of the plunger rocks the rocker, D, back a little past the normal position; but in passing this normal position the cross end, 41^a, of the key which was depressed for setting the rotor, C, will fly up through the enlarged portion, 25^e, of the slot, 25^d, and thereby the dog, 29, will be released as the key is retracted to its normal position, the stop, *d*, being rocked back past the rear end, 29^c, of said dog. In the concluding portion of said reverse rocking movement the wheel, 53^b, of the latch, 53, encounters an abutment, 73, on the plunger, positioned so that by such encounter the latch is rocked about its pivot and disengaged from the abutment, 25^c, on the rocker, D, whereupon the latter is rocked forward by the spring, 18, until the stop, *d*, encounters the end, 29^c, of the dog, 29^a; and at this position it will be seen that the spring, 18, will have been retensioned ready for its proper function of actuating the rocker, D, and rotating the rotor, and the latch, 53, will be held in the position shown in Figure 3.

For inking the printing face which has been set at printing position there is provided an ink-pad carrier, E, carried by the trunnions, 9^a, the side arms, 60, of said ink pad carrier being slotted as seen at 60^a, for limited vertical movement of the pad carrier with respect to the printing face. For carrying the pad carrier at a certain part of the operation the standard has on each limb a laterally projecting arm, 2^d, and in the end of said arms there is mounted a rock shaft, 70, having lever arms, 71, which extend in curved direction down and in toward the standard, and have cam slots, 72, which engage studs, 60^c, which project inward from the suspending arms, 60, of the ink-pad carrier. On each of the uprights, 2, 2, about at the level of the rock shaft, 70, there is pivoted a cam member, 80, having a cam slot, 81, for engagement of the trunnion, 9^a.

These cam members, 80, are each extended outwardly from their pivots in an arm, 83, to which is connected one end of a spring, 85, which is coiled around the shaft, 70, the 5 other end of the spring being engaged with the lever arm, 71, so that said springs react for lifting the ends of said arms, and thereby upholding the ink-pad-carrier to the limit of the slot, 60°, by which the ink pad 10 carrier is suspended on the trunnion. At the position of rest of the parts,—that is, with the plunger at its high position,—the cam slot, 81, at its upper end substantially coincides with the upper end of the vertical 15 slot, α' , in the standard upright, and extends obliquely thence down away from the side at which the arms, 71, are located. It will be understood, therefore, that at that position, the cam members, 80, are definitely stopped 20 at two points, viz., by their pivotal mounting on the standard and at the engagement of the said slots with the trunnions; and it will be seen, therefore, that the springs, 85, stopped on the arms, 83, operate substantially as if they were stopped on the standard, so that the springs operate to the full extent of their tensional reaction for upholding rock shaft arms, 71; and by reason 25 of the oblique direction of the upper part 30 of the cam slots, 81, with respect to the vertical direction in which the trunnions move in the down-stroke of the plunger, these springs react also to up-hold the plunger to a certain limited extent, and in 35 this respect supplement the action of the plunger-supporting spring, B⁵, at the upper position in the plunger stem. The cam slot, 81, has a bend about the middle of its length, as seen in Figure 15, the angular relation 40 of its two portions above and below the bend by reason of the position of the pivot on the cam member at one side of the vertical plane of the trunnion, is such that the lower portion is substantially vertical from the 45 time the trunnion passes said angle in the cam slot; and it results that the plunger-upholding action of the spring, 85, supplementing that of the spring, B⁵, diminishes as the plunger descends and becomes substantially 50 nothing, from the time the trunnion passes such bend in the cam slot. The purpose of this construction is to cause the plunger to be held snugly at the position of rest, without employing around the plunger stem a 55 spring so heavy as would otherwise be necessary, which would make the finishing portion of the printing stroke, when that spring is most compressed, objectionably difficult.

The purpose of providing the means de- 60 scribed for upholding the ink-pad carrier and allowing a range of movement of the plunger trunnions with respect thereto in the descending movement of the plunger, it will be understood, is to permit the rotation 65 of the rotor for bringing the desired print-

ing face into printing position without wiping or being dragged over the pad, which necessarily is in a position to have the printing face pressed upon it for inking after said printing face has been brought to printing position. But it is also necessary that the inking pad which is held in the position described while the printing face is depressed into contact with it, should then withdraw from the printing face in order 70 that it may afterward be swung aside without dragging or wiping over said printing face; and for this purpose and to provide means for swinging the printing stamp out of the path of the printing face after the 75 inking has been effected, there is provided upon each trunnion a linkage comprising two links, 100 and 110, the former having an elongated slot by which it is hung upon the trunnion, the latter being pivoted at its 80 lower end to the side of the pad carrier, the two links being pivoted together at 105, a point offset from the vertical line of said two end connections. The rock shaft arm, 71, at each side has a stud, 71^b, which engages a cam slot, 60°, in the upper part of the length of the adjacent ink pad carrier suspending arm, 60. The cam slots, 72, in the rock shaft lever arms, 71, are shaped as most clearly seen in Figures 12, 7, 8 and 9, 95 with two parts at an obtuse angle to each other. The part of the downward movement of the ink pad carrier which occurs on the depression of the plunger after the stamp reaches the ink pad carrier, swings 100 the lever arm, 71, down while the studs, 60° are traversing the initial directly transverse part of said slot, the studs being at this part of the movement the actuating or driving element, and the lever arm serving by the 105 resistance of the springs, 85, to keep the ink pad up against the stamp for inking the latter, and if the ink pad yields enough, to keep the lower end of the slot, 60°, of the ink pad carrier arm up against the trunnion, 110 110°. After a certain amount of depressing movement adequate for insuring the inking the stamp, it is necessary that the ink pad should descend faster than the stamp, so as to clear the latter before swinging out of the 115 path, and thus avoid wiping and smearing the stamp; and to accomplish this is the purpose of certain details of the construction as will now be pointed out. The upper links, 100, have each an arm, 103, which 120 overhangs the corresponding lever arm, 71, in position to encounter said lever arm when the stud, 60°, arrives at the bend in the slot, 72; and at the point of such encounter the lever arm has its encountered edge deflected upward to form what may be called a controlling cam as seen at 71^c. At this stage of the movement,—that is, when the stud, 60°, reaches the bend of the slot, 72, the pressing of the stamp upon the ink pad 125 130

is completed and the stamp is inked, and the pad could be withdrawn from the stamp preparatory to swinging it aside. But at this stage the trunnion, 9^a, is at the lower end 5 of the slot, 60°, in the ink pad carrier suspending arm, and as far as this engagement is concerned, any depression of the plunger will depress the ink pad carrier only to the same extent, and will not operate to separate the pad from the stamp. But the linkage, 100 and 110, constitutes an additional connection between the plunger and the ink pad carrier; and the upper link, 100, now has its arm, 103, resting against the face 15 of the cam upraise, 71^e of the lever arm, 71, and further depression of the plunger pressing down by means of said arm, 103, upon the lever arm, causes it to be swung aside and its said cam, 71^e, to be pressed against 20 said lever arm, 103, swinging the lever, 100, about its pivotal engagement with the trunnion in a direction to swing the pivotal connection of the links, 100 and 110, inward toward the line of their extreme pivots to 25 the plunger and to the ink pad carrier respectively, thereby straightening the linkage and thrusting the ink pad carrier downward with respect to the plunger and stamp. The oblique portion of the slot, 72, accommodates this movement and the continued 30 engagement of the stud, 60°, in said slot, 72. At this part of the action the cam slots, 60°, in the ink pad carrier arms, afford clearance for the studs, 71^b, in the movement of 35 the lever arm to a point at which the studs, 60°, reach the ends of the oblique part of the slot, 72. By this time also it will be seen that the upper ends of the slots, 60°, have reached the trunnions, 9^a, and the ink 40 pad is thereby prevented from descending farther in advance of the stamp. Up to this point the ink pad carrier had been held to a direct vertical path of descent by the engagement of studs, 60°, which project from 45 the ink pad carrier arms, 60, in vertical slots, 6°, in the standard limbs, 6; and it has been thereby prevented from swinging aside to clear the stamp; but at the point now reached,—that is, when the studs, 60°, are at 50 the ends of the oblique portion of the slot, 72, and further descent of the plunger if it can operate on the ink pad carrier to depress it, will cause it to be swung laterally by its engagement with the rock shaft arm, 71. But, as noted, the trunnions, 9^a, are now 55 at the upper end of the slot, 60°. The linkage, 100 and 110, however, constitutes a connection on the plunger to the ink pad carrier which will serve to pull the ink pad carrier down and cause it to be swung aside by the control of the lever arm, 71, if said 60 linkage can be prevented from folding; and this is accomplished by the engagement of the arm, 103, of the upper link, 100, with 65 the cam upraise, 71^e, of the lever, 71, said

cam upraise being shaped in view of the two movements which are occurring, namely, the depression of the link 100, by the plunger, and the lateral swinging of the arm, 71, about its rock shaft axis, to cause the linkage to remain substantially unchanged in its extension throughout the lateral swinging of the ink pad carrier which results from the further depression of the plunger to bring the stamp to printing position. 70 75

In the return movement of the parts under the reaction of the spring around the plunger stem and the spring, 85, the various movements are performed in reverse order to that above described, and in this return 80 action, the oblique portion of the slot, 72, in the lever, 71, becomes the driving element in the engagement of said slot, with the stud, 60°, and effects the control of the relative position of the parts which in the 85 depressing movement is effected by the arm, 103, with the cam upraise, 71^e. It may be observed that although so long as the spring, 85, is operating with proper stress upon the lever arm, 71, the form of the slot, 60°, except in so far as it affords a clear path for the stud, 71^b, is without function, said slot and stud cooperate at the end of the slot for the active function of stopping the lateral 90 swinging movement of the ink pad carrier 95 when it is swung aside for clearing a path for the stamp; and said slots being made in the form required as a path for the stud in the movement described, and without any excess of width beyond affording the path 100 for the stud, will operate for controlling the movement of the ink pad carrier in both directions; and for the purpose of these movements, except for up-holding the ink pad carrier while the stamp is pressed 105 against it for inking, said spring, 85, may be considered as having only the function of keeping the parts in non-rattling relation throughout the movements in both directions. 110

Certain details of the construction require mention.

For insuring exactness of position of the stamp at the limit of the printing stroke the bottom bar, 3, of the standard has at the margin of the space, 3^a, through which the stamp protrudes for printing an inclined lip, a², with which the stamp if it is in any instance displaced from exactly correct position, will collide and will be thereby directed back to true position. 115 120

For convenience in removing and replacing the ink pad, 4, and for insuring its retention in place, it is mounted in a pan, e, which has a handle lug, e¹, at one side and a stud, e², at each end, and the carrier, E, has a pair of springs, e³, adapted for easy engagement and disengagement of the studs, e², in inserting and removing the pan. 125

To afford desirable footing for the spring, 130

B^b , on the plunger stem, B^1 , in the standard stem, A^1 , said stem, A^1 , is slotted as seen at b^1 , and through said slots there is introduced edgewise and then turned to crosswise position a stop washer, 90, having necks, 90^a , at which it engages the margins of the slots, b^1 , and heads, 90^b , outside the stem. It will be understood that this washer stopped by its heads 90^b , resting on the part, a , at the bottom of the slots affords a footing for the spring around the outer circumference thereof.

Provision may be made for repeating the imprinting operation with any selected 15 stamp a number of times without resetting. Provision may also be made for correcting an erroneous setting without going through the operation of printing with the erroneous stamp. Devices for these purposes may be 20 added to the structure already described, as illustrated in Figures 19 to 25, which will now be described.

For repeating without resetting there will be provided a trip arm or member, 120, having an elongated slot, 121, by which it is mounted on the shaft, 9, between the arm, 52, and the right-hand arm, 25^a , of the rocker, 25. This member, 120, is additionally guided for reciprocating on the shaft, 9, 30 through the range of the slot, 121, by a stud, 122, mounted on the inner side of the proximate links, and a spring, 123, stretched between the stud, 122, and an anchor pin, 124, on the member, 120, tending to retract said 35 member outward; but a dog, 125, fulcrumed on the limb, 25^a , of the rocker, and having its nose, 125^a , engaging a shoulder, 120 a , on the member, 120, operates to hold said member at in-thrust position as seen in Figure 40 20. The member, 120, extends out through a slot 25^x , in the keyboard 7, and is bent at right angles to afford a label-bearing surface as seen at 120^b , being marked to indicate its purpose with the word "Repeat." At its 45 inner end the member, 120, has an arcuate edge formed at 120^c , curved about the center of the shaft, 9, when said member, 120, is at in-thrust position seen at Figure 20. From the position stated of the member, 120, it results that said arcuate edge, 120^c , is in the 50 plane of the dog, 53, and said dog is extended beyond its fulcrum in an arm 53^x , which rides on said arcuate edge throughout the entire swinging movement of the dog as 55 carried with the rotor, and thereby the catch nose, 53^a , of said dog is held out of the path in which it might engage the abutment, 25^f , and in consequence said abutment, not being engaged, the rotor is not rocked back to its 60 position upon the return or up-stroke of the plunger, and consequently the stamp which has been set at printing position remains so set and its imprint may be repeated as often as desired until the operator releases the dog, 65 125, and for that purpose said dog has its

outer end bent at a right angle and forming a finger, 125^b , which projects through a slot, 25^y , in the right-hand limb of the plunger segment, as shown in the part labeled "Release" in Figure 24.

For correcting an erroneous setting, there will be provided an arm, 126, pivoted on the shaft, 9, intermediate the inner side of the left-hand limb, 6, of the plunger, and extending out through a slot, 7^a , in a segment 75 key-board, 7, and exteriorly provided with a right-angularly bent terminal labeled "Error," see Figure 25. On this lever, 126, there is pivoted a dog, 127, having a hook-nose, 127^a , which engages a stud, 27^a , projecting from the outer side of the gear 27. At the rest position of the parts, the lever, 126, stands at the top of the slot, 7^a , and the hook, 127^a , stands as seen in Figure 21, in advance of the stud, 27^a , the arc of travel of 85 said stud with the gear, 27, as many degrees as the maximum rotation of the gear, 27, for setting the highest number stamp. If an erroneous setting is made, the operator depresses the lever, 126, along the slot, 7^a , 90 causing the hook, 127^a , to pick up the stud, 27^a , at whatever position said stud may occupy, according to the number of the key which was erroneously operated, and retracts the gear and thereby the segment 95 rocker and rotor to rest position, ready for the operation of the proper key.

We claim:

1. In a hand stamp in combination with a frame and plunger for reciprocating the 100 stamp bearing member, a rotor having a multiplicity of paraxially extending faces for carrying printing means; means for automatically adjusting the rotor to set a selected printing face at printing position; a cylindrical segment mounted on the plunger for oscillation about the segment axis; a spring which reacts for rocking the segment away from a predetermined normal position; a catch for locking the segment in 105 said normal position; a plurality of manual keys mounted on the plunger and means by which each of the keys releases the catch; stops distributed along the length of the segment and at graduated angular intervals 110 there-around, keys having means positioned in the paths of movement of the stops respectively in the rocking of the segment for encounter of the respective stops when the keys are operated for releasing the catch, 120 and means by which the rocking of the segment proportionately rotates the motor.

2. In combination with the structure defined in claim 1, means for retracting the plunger, and means operated by the return 125 movement of the plunger for rocking the segment back to normal position against the resistance of the spring and thereby retensioning the spring.

3. In the construction defined in claim 1, 130

foregoing, the segment axis being coincident with the rotor axis, and the segment having radius arms for reaching the axis, the means for rotating the rotor being an interior rack 5 on the segment; an axially positioned pinion on the rotor, and a gear journaled on a segment radius arm meshing with the rack and with the pinion.

4. In combination with the structure defined in claim 1 foregoing, a device mounted and connected for being rocked about the rotor and segment axis by the reciprocation of the plunger, and means by which said device engages the segment in the return rocking 15 movement of said device upon retraction of the plunger, to restore the segment to normal position and tension the spring.

5. In combination with the structure defined in claim 1 foregoing, a rocker pivoted 20 about the segment axis and swinging alongside one of the segment radius arms; means for oscillating the rocker by the reciprocation of the plunger; a dog carried by said rocker; an abutment on the segment radius 25 arm positioned for engagement of the dog in the movement of the rocker caused by the retraction of the plunger.

6. In combination with the structure defined in claim 1 foregoing, a rocker pivoted 30 about the segment axis and swinging alongside of one of the segment radius arms; means for oscillating the rocker by the reciprocation of the plunger; a dog carried by said rocker; an abutment on the segment 35 radius arm positioned for engagement by the dog in the movement of the rocker caused by the retraction of the plunger; an abutment on the plunger and a cooperating tripping abutment on the dog which collides 40 for disengaging the dog from the segment at the finishing part of the retraction of the plunger, and consequent retraction of the rocker after the re-engagement of the segment locking catch.

45 7. In a hand stamp, in combination with the frame or standard and a plunger mounted for reciprocation therein, a stamp-carrying rotor journaled in the plunger; a cylindrical segment disk exterior to the rotor 50 having radius arms for mounting it for oscillation about the rotor axis; means for rotating the rotor proportionately by the rocking of the segment; a spring reacting for rocking the segment in one direction; a catch 55 for locking the segment at a predetermined limit of its rocking range in the other direction; a catch-releasing member; a multiplicity of manual keys mounted on the plunger each adapted singly to release the catch 60 and arrest the segment; and stops on the segment co-operating with the keys respectively for arresting the segment each at a different position in its range of the rocking caused by the spring.

8. In the construction defined in claim 7, 65 foregoing, the stops on the segment being the ends of slots therein, in which slots respectively the different keys are entered by the catch-releasing movement of the key bar.

9. In the construction defined in claim 7, 70 foregoing, the stops on the segment being the ends of slots therein in which slots respectively the different keys are entered by the catch-releasing movement of the key bar; the catch comprising a bar which extends 75 across the segment and has side arms folded transversely to the axis and which is pivoted by means of said side arms to the plunger side bars, one of said side arms being extended to engage an abutment on the segment.

10. In a self-inking stamp in combination with a standard, a plunger and a printing stamp carried thereby; an ink-pad-carrier supported by the plunger; a lever arm having a fulcrum offset from the plunger's path and its free end operatively engaged with the ink-pad-carrier; means connecting the lever arm with the plunger for swinging said arm by the plunger's movement; a linkage 85 for connecting the plunger and the ink-pad-carrier, said lever arm and one of the links having members which co-operate for straightening the linkage to depress the ink-pad-carrier relatively to the plunger in the 90 plunger-caused movement of the lever arm.

11. In the construction defined in claim 10, foregoing, the lever arm being spring-upheld for upholding the ink-pad-carrier against the stamp prior to the depression of the ink-pad-carrier by the straightening of the linkage.

12. In the construction defined in claim 10, foregoing, the standard having a vertical guideway for the ink-pad-carrier, and said ink-pad-carrier having an abutment engaging said guide-way, said guide-way being cut away at one side to form an escape-way for the abutment to permit the ink-pad-carrier to swing aside onto the path of the stamp at the limit of the relative depression of the ink-pad-carrier caused by the straightening of the linkage; the lever arm's engagement with the pad carrier being by a slot in one of said parts, and a stud on the other part engaged with the slot, said slot for stopping the movement of the stud at the point in the plunger's descent at which the abutment of the pad carrier reaches said escape-way; whereby at that point the lateral swing of the lever arm carries the pad carrier laterally out of the path of the stamp.

13. In the construction defined in claim 10, foregoing, the pad carrier having two stud-and-slot engagements with the lever arm, said slots being relatively shaped to mutually defeat movement of their respective studs back from the ends of the slots

by turning the pad carrier at its engagement with the plunger at the swung-aside position of the carrier.

14. In a hand stamp in combination with 5 a supporting frame or standard, a plunger for carrying a printing stamp, a rotor by means of which the printing stamp is carried; a rocker mounted on the plunger for rocking about the rotor axis; gear connections 10 between the rotor and rocker; a spring operating through said gear connections for relatively rotating the rocker and rotor about a common axis; means carried by the plunger, (a) for releasably locking the rocker at 15 predetermined normal position, and (b) for limiting the relative movement of the rocker and rotor under the impulse of the spring.

15. In the construction defined in claim 14, foregoing, the gear connections being 20 constructed to rock both the rocker and the rotor relatively to the plunger, the releasable locking means comprising a plurality of manually-operable keys carried by the standard, and the limiting means being differently 25 positioned stops on the rocker for co-operating with the several keys respectively.

16. In the construction defined in claim 14, foregoing, the gear connection being constructed for rotating the rocker and rotor 30 relatively to the frame or standard, the releasable locking means comprising a plurality of manually-operated keys carried by the plunger; the rocker having a cylindrical segment web and the limiting means being differently 35 positioned stops on said web co-operating with the keys respectively.

17. In the construction defined in claim 14 foregoing, the gear connection being constructed for rotating both the rocker and the 40 rotor relatively to the frame or standard, the releasable locking means being a plurality of manually-operated keys carried by the plunger; the rocker having a cylindrical web provided with a plurality of slots extending 45 in circumferential direction therein, said slots being positioned for entry of the keys respectively and being of different lengths from the points of entry by the keys; the limiting means being the ends of said 50 slots remote from the respective points of entry.

18. In the construction defined in claim 14, foregoing, the gear connections and the trunnions being constructed for rocking 55 both the rocker and the rotor relatively to the frame or standard, the releasable rocking means, being a plurality of manually-operable keys carried by the plunger; the rocker having a cylindrical segment web 60 provided with a plurality of circumferentially extending slots adapted to be entered by the keys respectively, the keys having each the end which enters the slot furnished with a projection for engaging behind the 65 margin of the slot inside the same, and the

slots having each a lateral enlargement at the point of entry for admitting said projection of the key, whereby the key is held engaged by the cylindrical segment during the rocking of the latter.

70

19. In a hand stamp, in combination with a frame or standard and a plunger reciprocating therein; a printing stamp carrier on the plunger adjustable about an axis thereon; a rocker on the plunger operatively related to the stamp carrier for adjusting it about said axis; means on the standard for controlling the rocker in said adjustment to bring a selected stamp into printing position independently of the depression of the plunger for printing; a device carried by the plunger for restoring the rocker to normal position, and actuating means on the standard for operating said restoring device on the plunger after each printing stroke.

85

20. In the construction defined in claim 19, the rocker-restoring device being a member mounted for rocking about the rocker axis; a catch carried by said rocking member; co-operating means on the standard and said member respectively for rocking the latter in the reciprocation of the standard, the rocking means being positioned for engaging the catch in the movement of the latter derived from the retraction of the plunger.

90

21. In the construction defined in claim 19, the rocker restoring device being a member mounted for rocking about the rocker axis; a catch carried by said rocking member; co-operating means on the standard 100 and said member for rocking the latter in the reciprocation of the standard, the rocker having means positioned for engaging the catch in the movement of the latter derived from the retraction of the plunger, and means on the standard for disengaging the catch in the closing part of said rocker-retracting movement of the plunger.

105

22. In the construction defined in claim 19, foregoing, the controlling means on the plunger being a plurality of manual keys and a dog operable by any key singly for releasing the dog, the rocker having an abutment which the dog engages to hold the rocker at rest position; the means for restoring the rocker consisting of a second rocking member and a catch thereon adapted for engaging the first rocker in the return movement of the second rocking member to rest position, and means on the standard 115 for encounter of the heel of the catch in said return movement of the catch-carrying rocker, positioned for said encounter in the finishing of the retraction of the plunger.

120

23. In a hand-stamp in combination with a frame or standard, a plunger and a plurality of printing stamps operated thereby; a printing stamp carrier mounted on the plunger for rotation about an axis therein to position the selected stamp at printing 130

125

position; a spring for rotating the stamp carrier about its axis; means for locking the stamp carrier at a predetermined normal position; key-operated means for releasing the carrier-locking means; a plurality of manual keys adapted for operating singly said releasing means, and carrier-arresting means co-operating with the keys respectively for arresting the released stamp carrier at variant positions corresponding to the several keys respectively, for locating at printing position the stamp corresponding to the operated key.

24. In a hand stamp in combination with the ink pad carrier, a pan for holding an ink pad having at opposite ends studs projecting for engagement with the carrier parts, the carrier having at each side a spring finger having one end free for entry 20 of the studs into engagement therewith.

25. In a hand stamp comprising a standard and a stamp-carrying plunger therein, a rotor in which the stamps are rotatably mounted in the plunger, the standard having a bottom plate apertured for protrusion of the stamps for printing and an inclined lip at one lateral margin of said aperture, for encounter of the stamp on the rotor to guide it to the aperture.

26. In a hand stamp in combination with a standard having a tubular stem, a plunger having a stem extending through the tubular stem of the standard, a coiled spring around the plunger stem within the standard stem; means on the plunger stem for stopping the upper end of the spring, the standard stem having opposite longitudinal slots, and a stop washer for the lower end of the spring having a middle portion fitting 40 within the standard stem and opposite slot-engaging lugs notched adjacent to said mid-

dle part for engagement with the side walls of the tubular standard stem, and said middle part being apertured for the plunger stem.

27. In combination with a stamp-carrying rotor, the dog for engaging it to return it to initial position, and a hold-out member having an arcuate edge mounted for movement on the rotor shaft, the dog being extended for encounter with said arcuate edge, and means for releasably locking the dog at the position in its range of movement on the shaft at which said edge stops the dog by the engagement of the rotor.

28. In combination with a stamp-carrying rotor, and the means for rotating it for setting a selected stamp at printing position, a lever fulcrumed on the rotor shaft, a dog carried by said lever, and means on a part 60 concerned in the movement of the rotor for setting it positioned for engagement by the dog in the movement of the latter in reverse direction of the setting movement of said part.

29. In combination with the stamp-carrying rotor and the means for rotating it for setting a selected stamp at printing position, a lever fulcrumed on the rotor shaft, a dog carried by the said lever; a gear and 70 pinion by which the rotor is rotated for setting it; the gear having a laterally projecting abutment positioned for engagement by the dog in the movement of the latter about the rotor shaft in the reverse direction 75 of the setting movement of the rotor.

In testimony whereof, we have hereunto set our hands at Chicago, this 18 day of January, 1921.

MAX RUMPF.
WILLIAM E. NIMZ.
